UNITED STATES PATENT OFFICE.

WALTER J. ST. ONGE, OF ELYRIA, OHIO, ASSIGNEE, BY MESNE ASSIGNMENTS, TO THE GARFORD MANUFACTURING COMPANY, OF ELYRIA, OHIO, A CORPORATION OF OHIO.

WARNING-SIGNAL DEVICE.

1,178,034.

Specification of Letters Patent.

Patented Apr. 4, 1916.

Application filed July 3, 1911. Serial No. 636,681.

To all whom it may concern:

Be it known that I, WALTER J. ST. ONGE, a citizen of the United States, residing at Elyria, in the county of Lorain and State of Ohio, have invented certain new and useful Improvements in Warning-Signal Devices; and I do hereby declare the following to be a full, clear, and exact description of the invention, such as will enable others skilled in the art to which it appertains to make and use the same.

My invention relates to a unitary structure, consisting of a lamp and warning signal device adapted to be employed on a vehicle, such as an automobile, motor boat or the like, one of the objects of my invention being the production of a compact structure of this kind which serves for both lighting and signaling purposes. The lamp either with or without a special reflector, may be mounted inside the resonator or bell of the horn, thus producing a unitary structure and reducing the number of fixtures attached to the vehicle, the number of parts to be kept clean and furnishing a better protection for the lamp. These advantages will be better appreciated when it is considered how many fixtures are secured to the sides of an automobile, when the fixtures are individual units.

Other objects of my invention and the invention itself will be best understood by reference to the following description when taken in connection with the accompanying illustrations showing specific embodiments of my invention, while the scope will be more particularly pointed out in the appended claims.

Figure 1 shows a cross section taken through one form of my invention. Fig. 2 shows a diagram of a preferred form of circuit arrangement to be used therewith. Fig. 3 shows a modification partly in elevation and partly in cross section. Fig. 4 shows a second modification, partly in section and partly in elevation. Fig. 5 is a front elevation of the form shown in Fig. 1. Fig. 6 is a perspective view of the same form.

Referring now to the drawings and to the embodiments of my invention shown therein, at 1 is shown a warning signal device, preferably an electro-mechanically actuated

horn, which is adapted to be used upon an automobile or other vehicle to which such devices are suited. This horn, in the form of my invention shown, consists of a frame plate 2, upon which magnets 3 are mounted. A diaphragm 4 is fastened to the frame by suitable fastening means, such as screws 5. At 6 is shown an armature which is controlled by the magnets and which is adapted to transmit blows to the diaphragm, preferably through an anvil 7. While I have shown this form of warning signal device, any suitable form may be used. A resonator 8 is mounted on the front of the horn and is preferably parabolic in shape. A parabolic reflector 9 is mounted within the resonator 8, being spaced therefrom, leaving an opening between the resonator and the edge of the reflector to permit the passage of sound waves outward. In the form shown in Figs. 1 and 5 spacing members 11 are employed for this purpose. These members are fastened at one end to the resonator 8 by screws or other suitable fastening means 12 and at the other end to the reflector 9 by suitable fastening means 13. A lamp 14 is mounted in the reflector 9, preferably in the focal point of said reflector. This point may also be the focal point of the resonator. A glass 15 is mounted in the opening end of the reflector 9, being clamped thereto by a member 16. The sound waves which are caused by the vibratile member 4, either pass directly through the opening 11 or else strike the back of the reflector 9. The back of this reflector is preferably polished so as to make the rear surface likewise a good reflector. Sound waves striking this surface, will be either reflected to the inner surface of the resonator or directly out through the opening 11. When striking the inner surface of the resonator 8, they will be reflected until they pass outward through the opening 11. It will thus be seen that the character of the signal will not be materially altered or the signaling interfered with by the presence of the reflector and lamp inside of the resonator.

In the form shown in Fig. 3, the rays of light emanating from the lamp 14 are reflected by the resonator 8, no special reflector being provided for the lamp, but the resonator 8 serving both functions. The

lamp is here supported by brackets 20, each connecting the lamp socket 21 to the rear of the resonator or the front of the frame 2'. While I have shown only a portion of the resonator as parabolic, it will be apparent that the entire resonator may be so made if desired, but it is desirable that the part which reflects the light waves, should be so made, the lamp being preferably mounted in the focal point of the parabolic part of the resonator as in the form shown.

In Fig. 4, the mounting of the lamp is similar to that shown in the form shown in Fig. 3, a lamp 14" being mounted in a socket 21' connected by brackets 20' to the frame piece 2" or the rear of the resonator 8". The lamp is provided with a special reflector 9". This reflector is, however, small in comparison with the resonator, so that some of the rays of light from the lamp are not reflected thereby. A portion of the resonator shown at 25 is made parabolic so as to reflect the rays of light which pass through the front of the reflector and impinge thereon. The lamp is placed in the focus of the portion of the resonator which is made parabolic, for the reason that when a source of light is placed in the focus of a parabolic reflector, the rays incident thereon are reflected exactly parallel to the axis. If it is desired, the entire resonator may be made parabolic, though it will be apparent that for the design shown in Fig. 4, the annular portion 25 alone, is sufficient.

The lamp and the signaling device, if an electrical signaling device is employed, may be connected up with the same circuit connections as shown in Fig. 2, where a common battery B is employed. This battery is connected by conductors 50, 51 and 52 with both the lamps and the signaling devices, the circuit of the signaling devices being controlled by a switch S and that of the lamps by a second switch S'.

It will be apparent that any form of warning signal device, that any form of lamp or that any form of reflector may be employed in connection with my invention and that numerous and extensive departures from the forms and details of the apparatus here shown may be made without departing from the spirit of this invention, the same being herein shown solely for the purpose

of clearly illustrating specific embodiments thereof.

55

Having thus described specific embodiments of my invention, what I desire to claim is:

1. In combination, a warning signal device, a resonator therefor, a lamp reflector, a lamp in said reflector and means to mount said lamp and reflector within the resonator, the walls of the resonator extending beyond the walls of the reflector when the reflector is mounted in the resonator, the light rays 60 from the lamp in the reflector impinging upon such extended portion of the reflector and being reflected thereby, said extended portions having a focal point and said lamp being mounted at the focal point thereof. 70

2. In combination, a warning signal device, a resonator therefor, the edge of said resonator being flared outward to reflect light rays, a light reflector mounted in said resonator, and a lamp in said reflector, said flared part reflecting the rays of light from said lamp. 75

3. In combination, a warning signal device, a lamp reflector, means to mount said lamp reflector in front of said warning signal device, a lamp in said reflector, a resonator for said warning signal device mounted in front thereof and extending beyond the reflector, said extending part reflecting light from said lamp, a part of the extended portion of the resonator having the same focal point and a curvature of the same nature as the reflector. 80 85

4. In combination, a warning signal device, a lamp reflector of parabolic curvature 90 mounted in front thereof, a lamp in said reflector at the focal point thereof, a resonator in front of said warning signal device and extending beyond the reflector, said extending part reflecting light from said lamp, a 95 part of the extended portion of the resonator being of parabolic curvature on its interior surface and having the same focal point as the reflector.

In testimony whereof, I affix my signature 100 in the presence of two witnesses.

WALTER J. ST. ONGE.
